UNITED STATES PATENT OFFICE.

WILLIAM ERASTUS WILLIAMS, OF CHICAGO, ILLINOIS.

METAL FASTENER.

1,201,008.

Specification of Letters Patent. Patented Oct. 10, 1916.

Application filed February 18, 1915. Serial No. 9,081.

To all whom it may concern:

Be it known that I, WILLIAM ERASTUS WILLIAMS, a citizen of the United States, residing at Chicago, in the county of Cook and State of Illinois, have invented a new and useful Improvement in Metal Fasteners, of which the following is a specification.

The object of my invention is to provide an improved device adapted to being driven into wood to bind the parts together, or to hold the wood itself against splits or checks that take place when the wood is seasoning, or under breaking strains.

Reference will be had to the accompanying drawings in which—

Figure 1 is a top view of the driving edge of my metal bar or strip. Fig. 2 is a side elevation of my bar. Fig. 3 is a cross section of the bar. Fig. 4 is an edge view of the bar, looking toward its cutting edge. Fig. 5 shows two pieces of wood joined together by pieces of my bars. Fig. 6 is the end of a stick of timber bound against splitting by pieces of my bar curved in outline. Fig. 7 is the end of a stick of timber bound with my bar against splitting when the bar is in the form of a letter S. Fig. 8 is a view showing a fault often found in driving strips.

In the drawing, 1 indicates the bar, 2 the cutting edge and 3 the driving face; 4 indicates transverse ribs or enlargements alternately spaced on opposite sides of the bar and serving a double purpose. Such metal

strips must have strength to hold the wood securely yet should not exert dangerous splitting force when they are driven, and for these reasons they should be wide and comparatively thin, giving great tensile strength with little splitting force due to their wedge-like action. With metal binding strips heretofore used it has been common to corrugate the strip forming wavy curves and rely on the kinks in the strip for the holding power, but if such strip be thin, strong tension causes it to bend and slip in the curved channel in the wood.

With my invention, the ribs 4, hold in the wood so securely that the full strength of the strip is secured whenever the wood covers a few of the ribs on each side of the joint, or split.

In driving a thin strip of metal edgewise into wood, the metal often bends over in spots where the hammer hits it as is shown by 5, Fig. 8 and causes the loss of a strip

or piece of metal, or else a poor result or failure of the iron. With my ribs 4, the strip is so stiffened that it readily drives into the wood with little or no danger of bending the strip over under the blows of the hammer.

Whenever a crack or indenture of any kind is made in wood it seems to be seized upon as the point of origin for a split or check whenever there is a tendency to split from any cause. Were I to place my ribs 4, opposite each other on each side of the strip, then should a crack start at a rib on one side, the same crack might appear at the rib directly opposite and make a continuous split on both sides of the iron.

By making the ribs alternate as I have shown, while a split may start at one rib, see 6, Fig. 6, it would not be likely to cross the iron but instead it may appear as a new crack, 7—on the other side of the iron, which is not as objectionable as were the crack to become continuous.

In Fig. 5, the strips are shown as straight pieces binding two pieces of wood together.

In Fig. 7, the strip is in the form of a letter S, in which latter case little benefit would be derived from the ribs 4, were they on one side only of the strip, as the chief load is borne on the inside of the curved ends of the S, and in that case the inside of one end would be smooth and pull through. With my strip the ribs being on both sides, the holding power of each end of the S, balance each other.

My strip with its alternate ribs allow the strip to be thin and yet wide enough for strength and be adapted to be driven safely and it will hold in the wood.

What I claim is:—

1. A wood binding bar consisting of a flat metal strip of a length many times its width having on each broad face transverse to its lineal axis, a series of integral ribs each forming similar opposite shoulders to afford the same resistance to slipping in either direction, whereby segments of any length cut from a stock strip are adapted for use.

2. For driving into wood to bind the same together, a flat metal strip having a plane body of uniform thickness provided on each of its opposite broad faces with a series of ribs extending from margin to margin perpendicularly to the strip's lineal axis and forming on each side of each rib a narrow shoulder perpendicular to the face from which the rib projects.

3. For driving into wood to bind together the parts into which it is driven, a metal strip having a plane body provided on each broad face with a series of like integral 5 ribs extending from margin to margin of the strip and perpendicular to the face and to the strip's axis, the ribs on each face being opposite the spaces between consecutive ribs on the opposite face, and both strips 10 and ribs being beveled near one margin to form an edge in the medial plane of the strip.

4. A bar for binding together adjacent portions of wood, consisting of a flat metal 15 strip having its broad faces parallel and provided with a series of abruptly projecting ribs approximately equal in width to the thickness of the strip and extending from side to side of the strip perpendicu-

larly to its axis, said body and ribs being 20 beveled oppositely to form a thin medial edge at one side of the strip.

5. A bar for the purpose set forth, comprising a flat metal strip of approximately uniform width and thickness having on each broad face a series of spaced ribs extending perpendicularly across said face and projecting substantially perpendicularly therefrom, the ribbed strip being beveled to a cutting edge along one of its margins. 25

In witness whereof, I have hereunto signed my name at Hammond, Ind., on the 15th day of Feb. 1915. 30

WILLIAM ERASTUS WILLIAMS.
